UNITED STATES PATENT OFFICE.

HENRI H. REINEQUE, OF LOS ANGELES, CALIFORNIA.

SHIRT.

1,383,855.

Specification of Letters Patent.

Patented July 5, 1921.

Application filed August 14, 1919. Serial No. 317,543.

To all whom it may concern:

Be it known that I, HENRI H. REINEQUE, a citizen of the United States, residing at Los Angeles, in the county of Los Angeles and State of California, have invented new and useful Improvements in Shirts, of which the following is a specification.

My invention is an improvement in shirts, and has for its object to provide an article 10 of the character specified, having interchangeable cuffs and interchangeable front plait, arranged to be connected to the shirt body or disconnected therefrom, so that those parts which become soiled most easily 15 may be removed and replaced by clean parts.

In the drawings:

Figure 1 is a perspective view of a shirt constructed in accordance with the invention;

20 Fig. 2 is a similar view of a portion of one of the sleeves;

Fig. 3 is a similar view of one of the cuffs;

25 Fig. 4 is a longitudinal section at the front plait;

Fig. 5 is a section at right angles to Fig. 4;

Fig. 6 is a transverse section of the sleeve at the cuff, showing the manner of connecting the cuff to the sleeve.

30 In the present embodiment of the invention, the shirt body 1 is of the usual construction, having the collar band 2 and the sleeves 3, and the lower end of the sleeves 3 instead of having cuffs permanently attached there-

35 to have interchangeable cuffs which may be attached or detached. The end of each sleeve is provided with a plain hem 4 and with a series of buttons 5, the said buttons being sewed to the inner face of the sleeve, 40 as clearly shown in Fig. 6.

The cuffs 6, one of which is indicated in Fig. 3, are formed from as many plies as may be necessary, two in the present instance and they have the usual button holes 45 7 for cuff-buttons. One of the plies has an extension flap 8 which is provided with a series of button holes 9 corresponding in number and spacing to the buttons 5 of the sleeves. This flap is buttoned into the sleeve

as shown in Fig. 6, and when so buttoned 50 into place the shirt sleeve will resemble the sleeve of the ordinary shirt so far as appearances go. The cuff shown is a turned-over cuff, but it is obvious that any other style of cuff might be used.

55 At the closing flaps at the front of the shirt the edges of the flap are merely hemmed, and one flap 10 is provided with a series of buttons 11, the said buttons being sewed to the flap in the usual manner. The other flap 12 is provided with a series of button holes 13 adapted to be engaged by the buttons 11. A series of interchangeable plaits 14 is provided, corresponding in color to the cuffs of the series and matching them 60 with any figure, and each of these plaits have a series of button holes 15 spaced to correspond with the spacing of the buttons 11. It will be evident that when this plait is buttoned onto the outermost flap of the shirt 65 it will provide a facing that will correspond in color and figure to the cuffs.

70 Preferably each pair of cuffs is formed from two plies of material of different color or of different figures and each front plait is similarly formed, hence each pair of cuffs and a corresponding front plait provides what is in effect two shirts, that is provides for two changes. The flaps 10 and 12 as well 75 as the front plaits 14 have registering button holes for receiving the neck collar button 16.

80 I claim:

85 A shirt comprising a body having a permanent bosom, the shirt having a front opening and fastening means for said front opening, cuffless sleeves associated with the body portion, detachable cuffs adapted to be associated with the sleeves and each having an extension flap adapted to be received 90 within the opening of the sleeve, fastening means arranged on the inner side of the sleeve and co-operating with the extension flap, and a detachable plait adapted to be arranged along the front opening of the shirt 95 and being releasably secured in position thereon by the fastening means of said front opening.

HENRI H. REINEQUE.
